UNITED STATES PATENT OFFICE.

AMOS CALLESON, OF BROOKLYN, NEW YORK.

BOTTLE FILLING AND SEALING MACHINE.

Application filed August 9, 1920. Serial No. 402,230.

To all whom it may concern:

Be it known that I, AMOS CALLESON, a citizen of the United States, residing at Brooklyn, in the county of Kings and State of New York, have invented certain new and useful Improvements in Bottle Filling and Sealing Machines, of which the following is a specification.

This invention relates to machines for 10 operating on as by filling and capping or sealing containers, as bottles, and it consists in certain improvements whereby the two organizations for filling and sealing are unified and brought into such relation to 15 each other as properly to synchronize in their operations on the containers and whereby such operations are carried on from start to finish entirely automatically and with the least amount of interruption 20 due to faulty action of apparatus.

In the drawings,

Figure 1 is a vertical central sectional view of the machine, the upper part of the capping machine and certain other parts appearing in elevation;

Figure 2 is a plan, the cover of a certain liquid receptacle being removed and the capping machine appearing in horizontal section in a plane just above the bottle turret; 30 Figure 3 shows principally one of the filling units, in side elevation, and Figures 4 and 5 show said unit in front elevation and in plan;

Figure 6 is a side elevation of one of said units on a larger scale and partly in section;

Figure 7 shows the ram and syrup pump of said unit in vertical section;

Figure 8 is a plan of said unit with its top removed;

40 Figures 9 to 14, inclusive, are sectional views on lines 9—9, 10—10, 11—11, 12—12, 13—13 and 14—14 of Figure 6;

Figure 15 is a plan and side elevation of the bottle-mouth-gaging element of the 45 lower part or member of the filling head;

Figure 16 is a vertical sectional view of the syrup-pump-actuating part of the ram;

Figures 17, 18 and 19 show details of the syrup pump piston;

50 Figure 20 shows in end elevation and vertical section a valve-fitting in the syrup delivery line;

Figures 21 and 22 show in side elevation, partly in section, and in plan a valve-fitting 55 in the water delivery line;

Figure 23 is a sectional view of means

whereby somewhat greater pressure than that in the main source of pressure may be attained in each bottle;

Figures 24, 25, 26 and 27 show details of 60 a switch-valve device for controlling the pressure for operating the ram;

Figure 28 is a rear elevation of one of two vertically adjustable pillars and the means thereon for moving the aforesaid device one way, i. e., to effect the working thrust of the ram, other parts connected with said pillar being shown in section;

Figure 29 is an elevation of what appears in Figure 28, viewing the same from 70 the right in that figure, and Figure 30 is a plan of the pillar;

Figure 31 shows in plan the upper and the lower members of a train of parts constituting the means for moving, as afore- 75 said, the switch-valve device;

Figure 32 is a front elevation and a plan of the top portion, and Figure 33 a front elevation of the lower portion, of the other pillar and certain parts thereon;

80 Figure 34 is a partly sectional plan of what appears in Figure 33;

Figure 35 shows a certain guide z;

Figure 36 is a vertical sectional view, 85 Figure 37 a plan of the valve-chamber, and Figure 38 a sectional view on line 38—38 of Figure 36, of the water inlet controlling means;

Figure 39 shows a certain pneumatic clutch-controlling means.

90 The front of the machine is the side toward the observer in Figures 1 and 2.

In Figure 1 A designates the base and B and C are the capping and filling machines mounted on said base.

95 The capping machine B may be any capping machine (for instance, that set forth in my application Serial No. 353,604) which has a rotary turret onto which the bottles are successively delivered and which, rotating on a vertical axis, supports them while they are being capped or sealed, as by vertically reciprocating capping means. This turret is indicated at a, being secured to a rotary vertical shaft b which is stepped in a suitable bearing in the base portion c, mounted on base A, of the frame of the capping machine. The capping machine has a table d flush with its turret a. The turret a carries a gear e which meshes with a gear f fixed on a vertical shaft g that is journaled in suitable bearings in frame c and table d.

and above the table has also fixed to it a star wheel *h* whose function it is to feed the bottles that have been filled onto the turret one after another, for which purpose it 5 somewhat overlaps the latter.

On the base *A* is secured the pedestal *i* of the filling machine *C*. The upper reduced portion *i'* of this pedestal forms a bearing for the sleeve or hub *j* of a turret 10 that includes a table *k* flush with table *d* and turret *a*, said sleeve having a cap *l* which obtains a thrust bearing on the top of portion *i'* of pedestal *i*. On the turret *j* *k* is carried a super-turret *m* including a hub 15 or upstanding sleeve *n* on which is superimposed a liquid tank *o* having a central compartment or reservoir *p* and an annular compartment or reservoir *q* (covered and thus hermetically sealed), the super-structure 20 *m n o* thus formed being adjustable vertically on the turret *j* *k* by means of a pair of screws *r* that are tapped into the super-turret and swiveled in turret *k* and are connected by a sprocket and chain transmission, 25 *s*, and may thus both be turned together, to accomplish the adjustment, on turning the shaft *t* suitably geared with one of the screws. The turret *k* has twenty-four bottle 30 gages *u*, and superturret *m* corresponding ways *v* to receive the hereinafter mentioned parts 95. Turret *k* has a gear *w* which meshes with the gear *f*. Turret *a* and starwheel *h* are each adapted for the reception 35 of eight bottles, as shown in Figure 2; as the filling operation of each bottle requires a longer period of time than the capping thereof (according to the present system, three times as long) the speed ratio of gear *w* to gears *e* and *f*, which are of the same 40 size, is as 1 to 3.

Deposited one by one on a suitable runway (not shown) the bottles are advanced onto table *d* by a chain conveyor *x*, and are shunted by the guide *y* shown in Figure 2 45 toward the turret *k*, to be thereupon received in the gages *u*; each bottle is shifted into its gage by the guide *z* shown in Figures 2 and 35, which is arranged to be wiped by the base of the bottle. The conveyor *x* may be driven 50 through suitable gearing 2 shown in Figure 2 so that the speed ratio of turret *k* and said conveyor is 1 to 3.

I may here remark that the machine shown 55 is adapted for filling bottles with carbonated water and syrup and that the carbonated water in the present instance is assumed to be cold and in its container (receiver *q*) is under a certain pressure suitably above atmospheric, though of course lower than the 60 source of supply (not shown). According to this invention the filling means is adapted to keep the water under that pressure or substantially that pressure while the water as an incident to the filling operation is subject to agitation, that is, until the water is 65

actually in the bottle, thus to prevent loss of its gas (after filling and up to and inclusive of sealing, since the liquid then undergoes little disturbance and but a comparatively small amount of surface thereof—represented by the diameter in the neck of the bottle—is exposed, such a precautionary measure is not required); that is, means is provided for keeping the desired pressure in the reservoir *q*, and means is also provided for forming a sealed connection between the reservoir and bottle during the transfer of the charge from the former to the latter, the charge, when released, flowing simply as the result of the action of gravity. Further, 70 the means for admitting the water to the reservoir and for delivering it therefrom, and for also delivering the syrup, to the bottle have been designed so as to avoid disturbance of the liquid as much as possible, 75 with consequent loss of gas and undesirable foaming.

The receptacle *o* has a supply pipe 3 for reservoir *q*, a part 3' of which is a depending axial extension of said receptacle and at its 80 lower end is telescoped into the end portion 4 of a pipe 4' which is connected with the supply of carbonated water (not shown). There is a syrup supply pipe 5 suitably connected with a syrup supply (not shown), 85 the downwardly extending part 5' of which is telescoped into a pipe 5'' axially arranged in and secured to the bottom of the receptacle *o* within its reservoir *p*, 6 being a constant-level float valve to control the delivery of 90 the syrup from pipe 5'' to said reservoir. There is further an air pipe 7 which takes air from a suitable source of air under pressure and has a downwardly extending portion 7' passing into and through the part 5' 95 of pipe 5 (the top of which is suitably sealed) and then laterally through reservoir *p* into reservoir *q*. Between revolving and fixed parts of the piping above referred to, as between 3' and 4, 5' and 5'' and 7 and 7', 100 are glands 8, 9 and 9', the gland 8 permitting telescoping movement of 3' and 4 when the superstructure *m*—*n*—*o* and its adjuncts are adjusted vertically, as explained.

The admission of the water to reservoir *o* 115 is controlled by a constant-level means of novel construction designed to produce a sudden but copious release and sudden and complete checking of the water to the reservoir as distinguished from a gradual release and checking with consequent incidental wire-drawing or squirting of the water, thus to reduce the agitation of the water as far as possible. In Figures 1, 36, 37 and 38 a horizontally elongated valve-chamber 10 forms the terminal, within reservoir *q*, of pipe 3, 11 being a port which leads to the space 12 of this valve-chamber from pipe 3 and 13 a port which forms a 120 valve seat in one end of this valve chamber 130

and discharges under a horizontal wall or baffle 14 which bridges a loop-extension 15 of the valve-chamber. A spring 16 seated against the other end of said chamber holds a valve 17 normally against said valve-seat, and the stem 18 of this valve protrudes and has its head 19 arranged over the baffle 14. Said head is connected by a toggle 20 with a screw 21 held adjustably by two nuts 22 in the end of loop-extension 15. There is a float lever 23 fulcrumed in the valve chamber 10, and a pivot 24 thereof is connected with the center pivot 25 of the toggle by a link 26 which is suitably forked at both ends to receive the float lever and toggle and has longitudinal slots 27 and 28 receiving pivots 24 and 25; interposed between the link and float-lever are springs 29. When, the liquid level in reservoir *p* falling, the float lever descends and brings the upper ends of slots 28 against the pivot 25 and so, thereupon compressing springs 29 (which are considerably more powerful than spring 16), starts to open, that is, "cracks" the valve 17, the pressures on opposite sides of the valve becoming thus balanced, the energy stored up in said springs moves the valve suddenly to the full-open position, and the water enters reservoir *q* in a stream which from practically the very outset is of the full volume afforded by port 13; the reservoir now filling and the float rising, the closing of the valve is deferred until the springs are fully extended and the link is raised until it acts to pull upward on pivot 25, and once this effects a buckling of the toggle spring 16, finally assisted by the pressure in 11, closes the valve suddenly. Both movements, opening and closing, of the valve therefore take place with practically no wire drawing or squirting and consequent disturbance of the water at the time the valve is near its seat.

Above each of the twenty-four gages and attached to tank *o* is an organization of parts, or unit, whereby the head of the bottle (its base being gaged by gage *u*) is brought to gaged position with respect to the turret, then by fluid-pressure derived from reservoir *q* a sealed space is formed by the combined spaces of the bottle and a filling-head and such sealed space is put in communication with reservoir *q* so as to balance the pressure in them, and then (provided such sealed space has been formed) the ways for the flow of the syrup and water opened. The filling-head is formed in two parts, upper and lower, the upper being carried by a ram operated by fluid-pressure derived from reservoir *q* and the lower having a sliding vertical movement and being adapted on descent of the upper part to be impinged thereby and thus forced against the bottle head to form the sealed space, whereupon there are established the com-

munications between the reservoir and said sealed space which result in balancing the pressures in the same and the flow of the liquids. Each unit includes a control device which is first actuated to switch the reservoir pressure as to that unit one way so as to cause the working thrust of the ram, with the operations mentioned that are the incident thereof, and then, after filling and before the bottle begins to move from the filling machine C to the capping machine B, is actuated to switch said reservoir pressure another way so as to return the ram.

The ram casing 30 of each unit is secured by screws 31 to the receptacle *o* (Figures 3 to 6 and 12). A ring 32 (Figures 1 and 2) surmounts and is secured to the several ram casings, forming a projecting flange concentric with the receptacle *o*, and this flange is received in the groove of a segment 33 secured to the tops of the pillars 34 and 35 which are arranged to slide (in adjusting the receptacle *o* up or down) on a pair of vertical posts 36, each of which latter is suitably fixed in a step 37 upstanding from and secured to the table *d* and one of which is forked at the top to receive the pipes 7 and 5. The front or near pillar 34 is shown in Figures 28 to 30 and the rear pillar 35 in Figures 32 to 34; only one of the two steps is shown, in Figure 33, being the one for the rear pillar 35, both steps being identical. The means carried by these pillars and the consequent purpose of their vertical adjustability will appear later.

The ram casing 30 contains two vertical cylinders 38 and 39. The cylinder 38 contains a piston 40 whose stem 41 has the filling head attached to its lower end. The cylinder 39, which is of greater area than the cylinder 38, has a piston 42 therein with which is formed what is in effect a sliding gland 43 to close the lower end of the cylinder and whose stem 44 protrudes downwardly. Connecting the two cylinders at the top, above their pistons, is a port 45, and from the bottom of the cylinder 38, upward through the ram casing and to the bottom of cylinder 39 leads a port 46 whereby the two cylinders may be put into communication with each other at points below their pistons (Figures 7 to 11). Means is provided for admitting the pressure in reservoir *q* to the opposite sides of the pistons, alternately, thus: The port of a pipe 47 (Figures 1, 3, 6 and 23) which is attached to a fitting 48, in turn attached to the receptacle *o* back of each ram casing, is extended downwardly into and terminates at the flat face 49 of a projection 50 of said casing (Figures 8, 9, and 10), said port being designated 51. Leading from said face 49 upwardly and to the top of cylinder 38 is a port 52, and leading from said face downwardly to the bottom of cylinder 38 is another port 53. When

a valve 54, formed as a disk with diametrically opposite grooves 55 in a face thereof which abuts the face 49, is turned one way communication is established from port 51 to the cylinders (above their pistons) via the port 52, and when the valve is turned the other way communication is established from said port 51 to the cylinders (below their pistons) via the port 53; thus the pressure in reservoir *q* is utilized for positively moving the pistons alternately down and up, and valve 54 acts in effect as a fluid pressure switch. Said valve, and its actuating sleeve 57, interlocked therewith (Figures 10 and 26-27) and having a bushing 58 pinned thereon and journaled in a part of the ram casing and a two-armed lever 59 interlocked with said bushing, are journaled on a stud 60 fixed in projection 50 and between the latter and the head 61 of said stud, a spiral spring 62, interposed between valve and bushing, holding the latter against seat 49. The means to turn lever 59 first one way and then the other as the filling unit is carried around is to be explained.

The throw of piston 40 is always the same—the full length of its cylinder—but the throw of piston 42 is variable at will in order to determine the amount of the syrup charge, whose delivery it effects; thus: The stem 44 (Figure 16) protrudes up through the glanded top of cylinder 39 into an upstanding nipple 63 fixed thereon into which is tapped a screw 64 which according as it is screwed up or down determines the elevation (by contact of stem 44 therewith) to which the piston can rise; to hold the screw as thus adjusted its head has a split contractible depending sleeve 65 which is tapering and threaded and has screwed thereon a clamping nut 66.

An integral part of ram casing 30 is a syrup cylinder 67, below and aligned with cylinder 39. At the top it has an inlet port 68 (Figure 20) and at the bottom a delivery port 69. The lower end of stem 44 has a head 70 (Figures 7 and 17) thereon which has slight vertical play between the spider 71 of the body part 72 and the packing part 73 of a piston in said cylinder, part 73 having an opening therethrough and forming at the top a valve seat with which head 70 coacts as a valve (Figures 7, 18 and 19). When the piston descends the valve closes and syrup is drawn into the cylinder above the piston through port 68, and when it rises this charge of syrup is transferred through the piston to below it, to be discharged through port 69 when the piston next descends. The port 68 communicates with the passage 74 of a valve fitting 75 removably attached to one side of the ram casing 30 and connected with the reservoir *p* by a pipe 76 (Figures 6 and 20), the fitting having a screw plug or valve 77 whereby the

syrup-flow may be cut off when for any reason the ram casing has to be removed for repairing the same or any of the parts carried thereby.

To the opposite side of the ram casing 30 is removably attached a valve fitting 78 (Figures 21 and 22) whose passage 79 directly connects with the reservoir *q* (Figure 6) and which has a screw plug or valve 80 whereby the carbonated water flow, which takes place through this fitting, may be cut off when, having detached the fitting, the ram casing is to be removed, as aforesaid. Passage 79 may if desired, for a purpose to be explained, be normally closed by a valve 81 which is held seated by a spring 82 interposed between a head piece 83 fixed on the upper end of the stem 84 of the valve and which is arranged to be depressed, to open the valve, by the descending gland 43 (Figures 6, 12 and 21).

A pipe 84 leads downwardly from the fitting 48 to and connects with a vertical bore 85 in the ram casing. This is the pipe for effecting balancing of pressures in the reservoir *q* and the hermetic space formed by the interiors of the filling head and bottle.

The upper part of the filling head includes a block 86 forming a valve-support (Figures 6 and 13) screwed onto the lower end of the stem 41. It carries a depending filling tube 87 and has two ports 88 and 89 (Figure 13) communicating with the filling tube and terminating in nipples 90 adapted to be connected with the outlet 69 of the syrup pump and with the passage 79 of the water fitting 78 by the flexible tubing 91 (Figure 6). Each passage 88 and 89 is normally closed by a spring pressed valve 92 having a stem 93 which protrudes downwardly through a gland 94.

The lower part of the filling head includes a block 95 (Figures 6 and 14) which is suspended from the ram casing by two rods 96 and 97 (the latter being tubular) which penetrate glands 98 affixed to said casing and exerting a friction grip on the rods; the structure formed by the block and rods may thus move vertically but will be held by friction at any elevation to which it is moved. An elastic block or gasket 99, which it is convenient to attach to the block 86, will cause depression of said structure when the upper part of the filling head has descended a certain distance; the rods penetrate freely said part 86 and fixed on one of the rods above said part is a collar 100 against which said part takes in moving upwardly thus to reset the previously depressed aforesaid structure. The tubular rod 97 connects the bore 85 and hence pipe 84 with a port 101 which leads to a valve chamber 102 (Figures 6 and 14) from which diverge two ports 103 terminating in diaphragm chambers 104 and also communicat-

ing with a chamber 105 through the lower wall 106 of which loosely extends the filling tube 87; each diaphragm chamber is closed by a diaphragm 107 normally held depressed or pressed inwardly by a plunger 108 which slides vertically in the plug 109 screwed into part 95. A valve 110, whose stem 111 protrudes upwardly and may be depressed by the part 86 of the filling head, is normally spring-held in position to close the communication through port 101 to the space in the lower part 95 of the filling head, which is formed by ports 103 and chambers 104—105. 112 is a guide for the bottle head 15 suitably bifurcated as to its lower portion to form a gage and formed annular at the top to support a yielding gasket 113 housed in part 95 and adapted to form with the bottle-mouth a sealed connection. When the space formed by the thus-combined interiors of the sealing head and bottle is thus closed the devices 108 become means to detect pressure in said space exceeding atmospheric pressure; said devices are vertically 20 aligned with and adapted to actuate the stems 93.

When each bottle is gaged as to its base by a gage *u*, as already explained, it is also gaged as to its head by the bifurcated or 30 gage portion of the guide 112, so after it begins, thus positioned, to move around on and with the turret *j k*, it sets in operative position means which moves the lever 59 one way and so causes the operations incident to filling to ensue. The lower portion 35 of the pillar 34 (see Figures 28 to 30) forms a guide for a horizontally movable slide 114 whose head 115 is normally held projecting into the path of the bottle (Figures 2 and 3) by a spring 116 interposed between a suitable shoulder on the slide and a projecting part 117 of said guide, 118. The slide is 40 pivotally connected to a lever 119 fulcrumed in the pillar and pivotally connected to a knuckle 120 which is held clamped between the head 121 of a sliding detector detent 122, guided and horizontally movable in the pillar, and a sleeve 123 (slidable on the 45 detent) by a spring 124 interposed between an enlargement 125 on the detent and said sleeve. The detent will thus move back and forth with slide 114. It may be desired to move the bottles past the slide 114 without 50 its movement causing the detent to project (dotted lines, Figure 28) in position to turn lever 59; wherefore the detent may be locked back by a catch or stop 126 leaving lever 119 to move the knuckle on the detent, idly, the catch being pivoted in pillar 34 and movable into obstructing relation to the forward side of the enlargement 125.

On the other pillar 35 is a detent 127 which trips lever 59, when the filling unit has proceeded so far, back again, switching 55 the pressure so as to elevate the ram and so

cut off the communication between reservoirs *p* and *q* and the filling head (Figures 2, 7 and 32).

On the pillar 35, at an elevation above the bottle heads but below that to which the lower ends of the filling tubes 87 ought properly to withdraw from the bottles, is a lever 128 which is held by a spring 129 with one end projecting into the path of any filling tube not thus fully elevated; this lever 70 when engaged by any such filling tube may by any suitable connections, as a lever 130 for actuating the controlling valve 130^a of a pneumatic clutch controlling means (a fragment of which is shown in Fig. 37 as 75 an air conducting pipe 130^b), be made to actuate the clutch of and so stop the machine before any injury could be done.

The fitting 48 communicates with the bore of a fitting 131 within the reservoir *q*, which bore contains a check valve 132 held seated against the pressure in said reservoir by a spring 133; between the check valve and the outlet end of the fitting 131 is an outlet from 80 said bore to reservoir *q* which is closed by a valve 134 seating toward the bore and in the present case held against its seat by gravity.

Operation: While the bottles being, as explained, successively fed to and positioned 95 on the turret *j k*, are carried around thereby to be fed to the sealing machine B by the star wheel *h*, they are filled with syrup and carbonated water subject to the pressure in the receptacle *q* which is kept substantially constant by the means 7, the constant-level means in said reservoir replenishing the liquid therein as fast as it is withdrawn; in the filling of each bottle the pressure increases somewhat above that in 100 the receptacle *q* on account of the means shown in Figure 23, as will appear.

The slide 114—115, which urges each bottle to position, with its base and head against the gages *u* and 112 as it passes, is caused by 110 the bottle to advance the detent 122 to the dotted line position in Figure 28, so that the switch valve 54, due to said detent turning the lever 59 and consequently the switch valve, switches the pressure in receptacle *q* (which was previously operative on the lower sides of the pistons 40 and 42) to above the ram pistons. The latter descend, so that gasket 99 impinges against and thus depresses the lower part 95 of the filling head 115 until gasket 113 impinges against the bottle mouth, whereupon gasket 99 becomes compressed and with the gasket 113 forms a sealed space comprising the interiors of the filling head and bottle, the filling tube 87 having meantime been thrust down into the bottle. In or upon forming this sealed space the valve 110 is unseated by part 86 of the filling head, wherefore the air or other gas above the liquid in reservoir *q* finds its way 125 130

to said space through the connection formed by 97, 85 and 84, the pressure in said reservoir and space becoming balanced. Then, having thus formed the sealed space and 5 raised the pressure therein and consequently caused the plungers or detectors 108 to be elevated, at the end of the downward movement of the upper part of the filling head with the ram and after compression of 10 gasket 99 the valves 92 will be unseated by the elevated plungers. (Unless the sealed space is properly formed and unless the pressure therein becomes raised to that in chamber *q*—above atmospheric—, with con- 15 sequent elevating of plungers 108, the valves 92 will not be unseated and so will not permit untimely release of the liquids.) Unseating of the valves 92 releases the water and syrup. The syrup should precede the 20 water into the bottle, and to this end I employ the valve 81 shown in Figure 21, which is adapted to be opened by the gland 43 engaging its head 83 when the syrup pump has about delivered its charge. When the 25 pressures become balanced in the aforesaid sealed space and reservoir *q* check valve 132 cuts off said space from the reservoir, so that as the liquids flow into the bottle there ensues a rise in pressure in said space; this 30 pressure is regulated by the weight of the valve 134 which is such that the valve will become unseated before the bottle would burst. The bottle having been filled it approaches the point where the lever 59 of its 35 filling unit will engage the fixed detent 127 and be turned thereby in the direction opposite to which it was turned by detent 122 to start the filling. The pressure now being switched by valve 54 to the under side of 40 the pistons 40 and 42 the latter rise. On account of the friction grip which the glands 98 maintain on the rods 97 the lower part of the filling head stands depressed as the upper part thereof now rises until the latter 45 by impinging the collar 100 elevates and so resets said part; consequently the valves 92 and 110 become reseated, preventing loss of the carbonated water and also the pressure in reservoir *q*. The rise of the piston 42 50 results in the charge of syrup which entered above the syrup pump piston on its previous down stroke passing through said piston to below it, ready to be delivered on the next filling operation.

55 When the turret *j*—*k* is adjusted to elevate or lower the tank *o* and the several units carried thereby to suit the height of bottles to be filled the pillars move up or down therewith, so that the means to rock the 60 levers 59 first one way and then the other and the lever 128 preserve always proper relation to said levers 59 and the bottles, respectively.

The power to rotate shaft *b*, and consequently turret *a* of the capping machine,

and, through the gearing described, the turret *j*—*k* of the filling machine and the bottle-advancing means *x*, is derived from a shaft 135 journaled at the top of the capping machine and suitably geared with shaft *b*; it 70 may be driven by the motor 136 through gearing 137, or by a belt on pulley 138, and it has the clutch, 139, hereinbefore referred to as controlled from lever 128.

Having thus fully described my invention, 75 what I claim as new and desire to secure by Letters Patent is:—

1. A filling apparatus including, in combination with a supporting means, a rotary container-conveying turret journaled therein 80 on a vertical axis, a carrying structure adjustable vertically on and rotating with the turret, another carrying structure coupled for movement vertically with the first structure but confined by the supporting means 85 against rotation with said first structure, a controlling device carried by and movable in one structure and an actuating device for the controlling device carried by the other structure, means, substantially vertically 90 aligned with the container being conveyed and carried by the first structure, for operating on said container, and means, controlled by the controlling device, for causing movement one toward the other as between the 95 second means and the container.

2. A filling apparatus including, in combination with a supporting means, a rotary container-conveying turret journaled therein 100 on a vertical axis, a structure adjustable vertically on and rotating with the turret, another structure coupled for movement vertically with the first structure but confined by the supporting means against rotation with said first structure, filling-charge-delivery means normally occupying a definite elevation in said first structure but depressible therein, means to rotate the turret, and means to control the last-named means having a controlling member arranged on the 105 second structure below the normal elevation of the filling-charge-delivery means but adapted to be actuated by the same when in rotating with said second structure, said filling-charge-delivery means passes said 110 member depressed below said elevation.

3. In combination, with a valve-support, means yieldable therein under pressure of a container exerted on said means toward the support for forming with the container a sealed space, and a valve carried by the support, said means having an inlet, controlled by said valve, for delivering fluid to said space and also having a valve-controlling detector movable therein by the pressure of the fluid in said space and adapted when so moved and on yielding of said means to engage and actuate the valve.

4. In combination, with a valve-support, means yieldable therein under pressure of a 125

- container exerted on said means toward the support for forming with the container a sealed space, and a valve carried by the support, said means having an inlet to said space for fluid under pressure and an inlet, controlled by said valve, for delivering liquid to said space and also having a valve-controlling detector movable therein by the pressure in said space and adapted when so moved and on yielding of said means to engage and actuate the valve.
5. In combination, two filling-head-forming parts one of which is yieldable toward the other and adapted on such movement to form with the other and a container a sealed space, and a valve on one of said parts, the other part having a valve-controlling detector movable therein by the pressure of the fluid admitted to said space and adapted 20 when so moved and on yielding of the yieldable one of said parts to engage and actuate the valve, one of said parts having an inlet, controlled by the valve, for delivering fluid to said space.
25. 6. In combination, two filling-head-forming parts one of which is yieldable toward the other and adapted on such movement to form with the other and a container a sealed space, and a valve on one of said parts, the other part having a valve-controlling detector movable therein by the pressure of the fluid admitted to said space and adapted when so moved and on yielding of the yieldable one of said parts to engage and actuate the valve, one of said parts having an inlet to said space for fluid under pressure and one of said parts having an inlet, controlled by the valve, for delivering liquid to said space.
35. 7. In combination, with a valve-support, means for forming with a container a sealed space, and a valve carried by the support, said means having an inlet to said space for fluid under pressure and an inlet, controlled by said valve, for delivering liquid to said space and also having a valve-controlling detector movable therein by the pressure in said space, said support and the part of said means having the detector being movable 50 one toward the other and the detector on such movement and when itself moved in said part by pressure in said space being adapted to engage and actuate the valve.
8. In combination, a reservoir for a fluid under pressure, a movable filling head, a fluid conductor connecting the reservoir and filling head, a fluid pump, a fluid conductor connecting the pump and filling head and by which the former delivers fluid to the latter, independently movable fluid operated means for actuating the filling head and pump, and fluid-conducting means connect-
- ing the reservoir with said fluid-operated means.
9. In combination, a reservoir for a gas under pressure and also for a liquid, a hollow filling head movable downwardly and including an upper part and a lower part yieldable toward the upper part, a gas conductor leading to the space of the filling head from the reservoir, a valve in one of said parts normally closing the conductor and adapted to be opened by the other part on yielding of the yielding one of said parts, a liquid conductor leading to the space of the filling head from the reservoir, and a valve in one of said parts normally closing the liquid conductor and adapted to be opened by the other of said parts on yielding of the yielding one of said parts.
10. In combination, a reservoir for a fluid under pressure, a cylinder and a fluid-moved piston therein, a filling head connected to and movable with the piston, another cylinder and a fluid-moved piston therein, a fluid-delivery pump having a piston connected to move with the second-named piston, valve-controlled means to convey fluid from the reservoir to each cylinder to actuate the piston therein, means to conduct to the filling head the fluid discharged by the pump, and means, controlled by a container placed in position to be filled by the filling head, for opening and closing the said conducting means.
11. In combination, a reservoir for a fluid under pressure, a movable filling head, a fluid-delivery pump including a cylinder and piston, means, operated by fluid pressure in said reservoir, to impart movements to the filling head and piston substantially together means to conduct to the filling head fluid discharged by the pump, and means, controlled by the pump piston, to control the flow through the first conducting means.
12. In combination, a reservoir for a gas under pressure and for a liquid, a filling head adapted to form with a container a sealed space, means, including gas and liquid conductors leading from above and below the liquid level in said reservoir to said space and through the filling head, for first admitting gas and then liquid to the container, the first conductor having a check valve opening toward said space and also an opening to the reservoir between the check valve and said space, and a normally closed valve for the said opening adapted to be opened by pressure in the conductor exceeding that in the reservoir.

In testimony whereof I affix my signature.

AMOS CALLESON.
